SHAFT-OPERATING MECHANISM.

1,266,234.

Specification of Letters Patent. Patented May 14, 1918.

Application filed November 20, 1917. Serial No. 202,982.

To all whom it may concern:

Be it known that we, JOSEPH ECKERT and JOHN KIRBY, Jr., citizens of the United States, and residents of Dayton, in the 5 county of Montgomery and State of Ohio, have invented certain new and useful Improvements in Shaft-Operating Mechanism, of which the following is a description, reference being had to the accompanying drawings, which form a part of our specification.

Our invention relates to an improvement in car brake mechanism, and more particularly to that class wherein the handle or operating lever when turned in one direction 15 rotates the brake-shaft, and when turned in an opposite direction will move independently of the brake-shaft.

The object of the invention is to produce a brake operating mechanism wherein a 20 ratchet wheel is fixed to or formed on the brake-shaft and a gravity actuated roller is employed to engage either of the teeth of the ratchet wheel to rotate the brake-shaft in a winding direction to apply the 25 brakes, and to automatically move out of the path of said teeth when the operating handle is moved in the opposite direction. The broad principle upon which our present invention is based is disclosed in United 30 States Letters Patent No. 508,025 issued to J. Kirby, Jr., Nov. 7, 1893, the present invention being designed to utilize the ratchet and roller principle shown in said patent in such manner as will permit the brake- 35 shaft to rotate in a reverse or unwinding direction, when the brakes are released, independently of the operating handle and casing, as contra-distinguished from the mechanism disclosed in Patent No. 1,162,994, 40 issued to Evans and Willing, Dec. 7, 1915, and to which mechanism we make no claim.

With this and other objects in view the invention consists in the various novel details of construction and combination of 45 parts hereinafter fully described in the specification, illustrated in the drawings and more particularly pointed out in the claims.

In the accompanying drawings forming part of the specification, and in which like 50 reference characters indicate corresponding parts, we have illustrated one form of brake handle embodying the essential features of our invention, although the same may be carried into effect in other ways without in 55 the least departing from the spirit thereof,

and in these drawings Figure 1 is a side view of our improved brake handle partly in section taken on the line C C of Fig. 2, showing the relative arrangement and position of the different parts, the operating 60 lever being shown, in solid lines, in its operative position and by dotted lines in its normal or inoperative position. Fig. 2 is a top plan view of our invention, partly in section, taken on line A A of Fig. 1. 65 Fig. 3 is a broken side view of the connecting end of the operating lever, detached. Fig. 4 is a cross section through the operating lever taken on the line B B of Fig. 1. Fig. 5 is a front view of roller housing and 70 mechanism for holding the brake shaft against retrograde movement, and Fig. 6 is a transverse section taken on the line X X of Fig. 1.

Referring to the drawings 1 is the brake 75 shaft, the lower portion of which is journaled in the car platform in the usual manner. Upon the upper portion of the brake-shaft there is rigidly mounted a ratchet member 2 secured to the shaft, preferably, 80 by means of pins 3, 4, and having a series of vertically formed ratchet teeth 5 around its exterior, as shown, the shaft being reduced at 6 and the member 2 conforming thereto. The upper end of the shaft 1 is 85 reduced in diameter at 7 forming a shoulder 8 upon which there is mounted a sleeve or cylinder 9 which surrounds the ratchet member 2 and is rotatable therearound independently of movement of the shaft and 90 the said member. This sleeve is open at its lower end and closed at its upper end except that it is provided with an upwardly extending collar 10 which surrounds the reduced portion 7 of the shaft, the sleeve being held in position on the shaft by means 95 of a nut 11 as more clearly shown in Fig. 1. At one side of and preferably integral with the sleeve there is formed a pair of laterally extending ears 12, 13, united by an extended 100 portion 14 of the top 15 of the sleeve. Between the ears 12, 13 there is pivotally mounted an operating lever or handle 16 by means of a bolt 17 which passes through aperture 18 in the ears and 19 in the lever. 105

The connecting end of the operating lever or handle is provided with a curved slot or chamber 20 having a top portion 21 constituting an extension of the lever as more clearly shown in Fig. 1. Free to traverse 110

the slot 20, in a vertical plane but restrained from movement in other directions, there is located a roller 22 which when the operating lever is in operative position, as shown in 5 solid lines in Fig. 1, rolls behind one of the ratchet teeth 5, the wall of the sleeve being cut away to admit of such movement and when the ratchet wheel and the roller are thus in engagement by turning the operating lever in the direction indicated by the 10 arrow in Fig. 2 the ratchet wheel and the brake shaft will be rotated in the same direction to set the brakes, while in moving the lever in the opposite direction the roller 15 will travel over the inclined surfaces of the ratchet teeth back and forth in the slot 20, thus allowing the lever and the sleeve to rotate in a reverse direction independently of the ratchet wheel and the shaft. To insure 20 the free and easy withdrawal of the roller when it is under pressure behind one of the ratchet teeth it is provided with a central perforation 23 through which and through the side walls of the seat 20 in the operating lever a pin 24 passes, the relation 25 of this pin to the perforation being such as to cause the withdrawal of the roller simultaneously with the downward movement of the operating lever; the diameter of the said 30 perforation being sufficient to prevent any interference with the required movement of the roller.

It will, of course, be understood that our invention contemplates setting of the brakes 35 through a number of partial revolutions of the brake shaft, that is to say, one stroke of the operating lever will rotate the shaft, say, one-quarter of a revolution, the lever then being reversed for another stroke, the 40 operation being repeated until the brakes are fully set, each partial revolution of the shaft being held against retrograde movement either by the customary pawl and ratchet device secured to the car platform 45 or by means presently to be described. Normally the operating lever hangs suspended on the bolt 17, in an inoperative position, its operative position being substantially horizontal as before indicated. The roller 22 is 50 protected from exposure by the extended portion 14 of the top 15 which in conjunction with the ears 12, 13 form a housing for the adjacent end of the lever regardless of the position of the latter. The operating 55 lever or handle is preferably formed hollow from a point near the aperture 19 to its free end, a channel 21, about one-half of the thickness of the roller, being formed through the solid portion 25 to provide an outlet 60 through the handle and the opening 26 at the end thereof for any foreign substance which may find its way into the roller slot 20. The said lever is further provided with a movable sleeve 27 having an annular 65 shoulder 28 and a rounded end 29 projecting

slightly beyond the face side of the lever and adapted to engage a corresponding detent 30 in the inner face of the ear 12, the said sleeve being pressed outward by a coil spring 31, the purpose of this arrangement 70 being to restrain the lever from dropping of its own weight while in operative position, thus relieving the operator from the necessity of holding the said lever against its inclination to drop to its normal position 75 during the brake setting operation, it being understood that a slight pressure on the lever will release the spring pressed rounded end 29 from the detent 30 and leave the lever free to drop by gravity to its normal position 80. This particular feature is shown, described and claimed in application of John Kirby, Jr., Serial Number 202,142, dated November 15, 1917, it being shown and described in this application merely to illustrate its adaptability to our present invention. It sometimes happens that when the brakes are set and the retaining pawl and ratchet mechanism released, the shaft refuses to unwind because of some irregularity; in such cases it becomes necessary to use force to free the brake chain and allow the shaft to perform its proper function. To provide for such emergency and adapt our improved mechanism to performance of 90 such reverse action we provide a pin 32 to be inserted through perforation 33 formed in the ears 12, 13 and the lever 16, which perforations when the lever is in operative position register with each other, the location of this pin being immediately behind the roller locks the same in engagement with the ratchet wheel and thus provides a means whereby the shaft may be operated in a reverse direction. A support 34 is provided 100 for the pin when out of service, and a chain 35 secures it against removal from the brake mechanism.

Heretofore in mounting hand brake operating mechanism on cars the ordinary 110 practice has been to secure a ratchet wheel to the lower part of the shaft, at the floor of the platform and which operates in conjunction with a pawl pivotally secured to the floor, to hold the shaft against retrograde movement during the operation of setting the brakes, and thereafter until the pawl is released by the foot of the operator, this mechanism being separate and apart from the brake operating mechanism at the 115 upper end of the brake shaft. One of the objects of this invention is to utilize the foregoing described ratchet and roller principle as a means by which the brake shaft is held against retrograde movement when 120 it is under tension and pressure on the operating lever is released and whereby the same may be released at the will of the operator, to which end we provide a second series of ratchet teeth 36 disposed at an 125 130

angle to those already described, located below the same, and extending outwardly therefrom, as shown. These ratchet teeth may be formed in a separate member 37 5 secured to the shaft so as to rotate therewith, or the members 2 and 37 may be formed in a single element as may best meet the judgment and convenience of the manufacturer, the number of teeth constituting the second 10 series being increased to provide for more frequent grips by the retaining element, about to be described. A shaft bracket 38, located below the second series of teeth, provides a bearing and guide for the shaft with- 15 in which the same is free to rotate, this bracket 38, terminates in a bracket-plate 39 adapted to be secured to any suitable support and having a branch 40 extending at an angle thereto, provided with an inwardly 20 projecting housing 41 forming an inclined roller chamber 42 and having an inclined slot 43 in each of the side walls thereof. Contained within this housing is a second roller 44 having a central perforation 45 25 and being free to move in and out of engagement with the ratchet teeth 36 and when in engagement therewith serves to hold the shaft against retrograde movement.

A bifurcated lever 46 having side walls 30 47 and a handle 48 straddles the housing 41 and is pivoted to the bracket plate at 49. A pin 50, the ends of which are riveted or otherwise secured to the side walls 47, passes through the housing 41 and through 35 the perforation 45 in the roller 44 and is operative in the slots 43. Thus when the roller is positioned behind one of the ratchet teeth 36 the shaft will be held against retrograde movement, and when in such position the pin 50 will occupy a position in close proximity to the rear side of perforation 45, so that when the bifurcated lever 46 is moved on its pivot 49 toward the rear, as shown by dotted lines in Fig. 1, 40 45 the pin 50 will traverse slots 43 and carry the roller 44 out of the path of the ratchet teeth 36 leaving the brake chain free to unwind and release the brakes, it being understood that during the winding process 50 the roller rides over the inclined surfaces of the ratchet teeth in the manner hereinbefore explained with respect to the roller 22. Forward movement of the bifurcated lever 46 is limited by a stop 51 formed on 55 the housing 41. rearward movement thereof being limited by the top edge of bracket plate 40.

To operate the foregoing described winding mechanism the operator raises the operating lever from its normal or inoperative position to its operative or horizontal position, during which operation the roller 22 automatically engages one of the ratchet teeth 5 and thereby establishes operative 60 connection with the shaft which can then be

rotated by turning the operating lever, said operative connection being broken by the dropping of the operating lever.

While we have illustrated and described our invention in connection with brakes for 70 railway cars it obviously is applicable for other winding purposes and we do not limit the use thereof to the particular purpose herein described.

Having thus fully described our invention, we claim:—

1. In a device of the character described, the combination of a shaft adapted to be rotated, a ratchet carried by the shaft and rotatable therewith, a member mounted upon 80 the shaft and rotatable thereon independently thereof, an operating lever in pivotal connection with said member, and roller mechanism adapted to engage said ratchet whereby the shaft may be rotated. 85

2. In winding mechanism of the character described, the combination of a shaft, a ratchet carried by and rotatable with the shaft, a member mounted upon the shaft and rotatable independently thereof, an operating lever in pivotal connection with said member, and a roller loosely mounted upon 90 said lever adapted to engage the teeth of said ratchet whereby the lever when turned in one direction will rotate the shaft 95 and when turned in the opposite direction will move independently of the shaft.

3. In winding mechanism of the character described, the combination of a shaft, a ratchet carried by and rotatable with the 100 shaft, a member mounted upon the shaft and rotatable independently thereof, an operating lever in pivotal connection with said member, and a roller loosely mounted upon said lever adapted to automatically engage 105 the teeth of said ratchet whereby the lever when turned in one direction will rotate the shaft and when turned in the opposite direction will move independently of the shaft. 110

4. The combination of a shaft having a ratchet therearound, of a member mounted on said shaft and rotatable independently thereof, an operating lever pivotally mounted upon said member, and roller mechanism 115 carried by said lever adapted to operatively connect said levers with said shaft whereby the same may be rotated.

5. The combination of a shaft having a ratchet therearound, of a member mounted 120 upon said shaft and rotatable independently thereof, an operating lever pivotally mounted upon said member, and roller mechanism carried by said lever to automatically connect said lever with said shaft whereby the 125 same may be rotated.

6. In combination with a shaft and a ratchet adapted to be rotated, a member mounted upon the shaft and rotatable independently thereof, an operating lever in 130

- 4
- pivotal connection with said member and having an elevated operative position and a depending normal position, roller mechanism carried by said lever arranged to engage said ratchet when the lever is elevated and thereby establish operative connection with the shaft to rotate the same, the said connection being broken by the downward movement of the lever.
- 10 7. In winding mechanism the combination of a shaft, a circular member having ratchet teeth formed in its peripheral surface carried by and rotatable with the shaft, a second member carried by and rotatable independently of the shaft, an operating lever in pivotal connection with said second member being normally suspended upon its pivot and adapted to be swung to a horizontal position, and roller mechanism carried by said lever whereby in raising the same to a horizontal position operative connection between the shaft and the lever will be established, said connection being broken by the downward movement of the lever.
- 15 8. In winding mechanism the combination of a shaft having a circular ratchet, a member mounted upon the shaft and rotatable independently thereof, an operating lever in pivotal connection with said member and normally suspended upon its pivot, a recess formed in one end of said lever and a roller located in said recess whereby when said lever is raised to a horizontal position said roller will automatically engage said ratchet and thereby establish operative connection between said shaft and said lever.
- 20 9. In combination with a rotatable shaft and ratchet, a member loosely mounted upon the shaft, an operating lever carried by said member and normally occupying a suspended position but movable in a vertical plane independently of said member, and roller mechanism carried by said lever, whereby operative connection between said shaft and said lever will be established when the lever is raised to operative position.
- 25 10. In combination with a rotatable shaft and ratchet, a sleeve loosely mounted upon the shaft and having members extending laterally therefrom, an operating lever pivotally mounted upon said members and normally suspended upon its pivot, and roller mechanism carried by said lever adapted to engage said ratchet and thereby establish operative connection with the shaft whereby the same may be rotated.
- 30 11. In combination with a rotatable shaft and ratchet, a sleeve loosely mounted upon the shaft and having members extending laterally therefrom, an operating lever pivotally mounted upon said members and normally suspended upon its pivot, roller mechanism carried by said lever adapted to automatically engage said ratchet when the lever is in operative position, thereby establishing operative connection between the shaft and the lever.
- 35 12. In combination with a shaft provided with means for its rotation, a member mounted upon and rotatable independently of the shaft, said member having lateral extensions forming a support for an operating lever, an operating lever pivotally mounted upon said extensions and normally suspended upon its pivot, roller mechanism carried by said lever adapted to engage said means and thereby establish operative connection whereby the shaft may be rotated, and a device for locking said roller mechanism in operative connection with the shaft whereby the same may be rotated in either direction.
- 40 13. In combination with a shaft provided with means for its rotation, a member mounted upon and rotatable independently of the shaft; said member having lateral extensions forming a support for an operating lever, an operating lever pivotally mounted upon said extensions and normally suspended upon its pivot, roller mechanism carried by said lever to engage said means and thereby establish operative connection whereby the shaft may be rotated, and a removable pin adapted to lock said roller mechanism in engagement with the shaft whereby the same may be rotated in either direction.
- 45 14. In brake operating mechanism the combination of a shaft adapted to be rotated, means whereby the same may be rotated to set the brakes, a support for the upper end of said shaft, a ratchet fixed to said shaft, and roller mechanism adapted to engage said ratchet to prevent retrograde movement of the shaft.
- 50 15. In brake operating mechanism the combination of a shaft adapted to be rotated, means whereby the same may be rotated to set the brakes, a support for the upper end of said shaft, a ratchet fixed to said shaft, roller mechanism carried by said support adapted to automatically engage said ratchet to hold the shaft against retrograde movement, and means for releasing said roller mechanism from said ratchet.
- 55 16. In brake operating mechanism the combination of a shaft adapted to be rotated, means whereby the same may be rotated to set the brakes, a support for the upper end of said shaft, a ratchet fixed to said shaft, a housing carried by said support, a roller loosely mounted in said housing adapted to automatically engage said ratchet and hold said shaft against retrograde movement, and means for releasing said roller from said ratchet.
- 60 17. A new article of manufacture, comprising an operating lever adapted to rotate brake setting mechanism; said lever being provided with means for pivotal attachment to the thing to be rotated and having

at its connecting end a slotted recess having an inclined bottom, a roller loosely mounted in said recess, and means for retaining said roller in said recess.

- 5 18. A new article of manufacture, comprising an operating lever adapted to rotate brake setting mechanism; said lever being provided with means for pivotal attachment to the thing to be rotated and having
10 at its connecting end a slotted recess having

an inclined bottom, a roller loosely mounted in said recess, and provision for receiving a removable pin adapted to lock said roller in operative engagement with the shaft to be rotated.
